UNITED STATES PATENT OFFICE.

LAURENCE G. WESSON, OF CHEVY CHASE, MARYLAND.

CONVERSION OF PINENE COMPOUNDS INTO ISOBORNYL ESTER AND CAMPHENE MIXTURE.

1,372,382.

Specification of Letters Patent. Patented Mar. 22, 1921.

No Drawing.

Application filed June 30, 1919. Serial No. 307,762.

To all whom it may concern:

Be it known that I, LAURENCE G. WESSON, a citizen of the United States of America, residing at Chevy Chase, in the county of Montgomery and State of Maryland, have invented certain new and useful Improvements in Conversion of Pinene Compounds into Isobornyl Ester and Camphene Mixture, of which the following is a specification.

The present invention pertains to the conversion of pinene hydrohaloids into other hydrocarbon derivatives suitable for use in the preparation of camphor and for analogous uses.

Among the objects of the invention is the acceleration of the transformation of the pinene group into the camphene or isobornyl group, by isomerization, and the performance of this reaction with the use of a minimum amount of chemicals, and while making possible the recovery of a substantial fraction (from 50 to 75%) of the HCl component of the pinene hydrochlorid, preferably used as starting material.

The most important object, however, is the reduction in the amount of resinous products produced during the transformation, as compared with the amounts ordinarily obtained by the use of zinc salts or of zinc.

These and other objects, which will be obvious from the description, are secured by the use of the novel procedure hereinbelow set forth.

In accordance with the process of the present invention, a mixture of pinene hydrochlorid and glacial acetic acid is heated together with a small amount of metallic zinc, the latter being used in the form of a coarse powder, granulated zinc or other relatively coarse pieces, in place of the more finely divided zinc dust. The reaction is carried out by heating the mixture of acetic acid and pinene hydrochlorid to vigorous boiling (say about 120° C.), and maintaining the mixture actively boiling until the completion of the reaction.

To more fully explain the invention, I give the following example, the same being for the purpose of illustrating specific procedure falling within the scope of the in-

vention, but the invention is not to be understood as limited thereto.

Pinene hydrochlorid is mixed with glacial acetic acid, in the proportions, respectively, of about 100 to 300 parts, by weight. 5 parts or less (2 parts ordinarily being preferred) of rather coarse zinc powder (say, about 10 mesh or coarser) are added, after the mixture has been heated to vigorous boiling, in a flask or receptacle provided with a reflux condenser, and the boiling continued for a period of about 18 hours.

During this operation, the zinc slowly dissolves, but a large proportion of the HCl component of the pinene hydrochlorid is evolved as a gas, and can be condensed or recovered for further use. This liberated acid can be used to produce more pinene hydrochlorid for a succeeding run.

At the end of 18 hours this product will be found to contain, in addition to the excess of the acetic acid used and the ZnCl₂ formed by the reaction of the zinc on a little of the hydrochloric acid, substantially over 70 parts, usually about 83 to 85 parts of isobornyl acetate, about 10 parts of camphene, about 5 parts of camphene hydrochlorid and less than 5 parts of resinous or high boiling point constituents, and not more than about 10 parts of unconverted pinene hydrochlorid. This mixture is preferably separated by fractional distillation, under reduced pressure, to separate the isobornyl acetate, camphene and camphene hydrochlorid mixture from the other ingredients, which mixture can be subsequently converted into camphor in any known way.

The unconverted pinene hydrochlorid and the excess acetic acid are returned to a subsequent run of the process.

During the carrying out of the process as above described, somewhat less than the total amount of zinc employed, will be dissolved. In other words, metallic zinc will be present during the entire procedure, while zinc chlorid will be present, after the operation is started. Zinc chlorid is known to be capable of effecting the isomerization of pinene hydrochlorid into isobornyl compounds, and also it has the effect of leading to the formation of resinous or high-boiling-point products. The contact of the reac-

tion mass, during the entire operation, with metallic zinc greatly reduces the degree to which this undesirable secondary reaction proceeds, thereby producing both a better 5 yield and a better product.

If an amount of zinc is used substantially larger than above stated, there is produced a correspondingly larger amount of zinc chlorid, and this leads to the production 10 of increased quantities of the resinous or high-boiling-point products, the amount of the latter in the product, increasing greatly as the amount of $ZnCl_2$ in the solution is increased.

15 The zinc may be all added at the commencement of the operation, or in small portions at intervals, as desired.

Of great importance is the smallness of the amount of zinc used. If a large amount 20 of the zinc were used, say, 20 to 30 parts, not only would the excess thereof be uselessly consumed, but the yield of the three products referred to (which in my process amounts to, say 80 or 85% of the theoretical) would be substantially reduced (say to 25 40-45%), also the hydrochloric acid would be practically all converted into zinc chlorid, and a much larger percentage of the resinous or high-boiling-point derivatives would be 30 produced.

It appears, from my researches on this isomerization, that large quantities of zinc chlorid and high temperatures (120° C.) 35 tend to greatly increase the amount of resinous products formed, while at low temperatures the degree of completeness of the isomerization drops off rapidly. That amount of the resinification which is due to the high temperature in the presence of a 40 minimum effective quantity of $ZnCl_2$ is accordingly to be considered as a necessary evil. The stopping of the operation at the end of about 18 hours (with the amount of zinc above stated) also reduces the amount of 45 the high-boiling-point or resinous products produced. If the process were continued for another four or six hours, the amount of pinene hydrochlorid left in the product would be less, but the amount of the resinous by-products would be enough greater to more 50 than offset the greater degree of completion of the reaction.

In carrying out the process, the time of heating can be varied more or less. With 55 about 2% of zinc 18 hours is generally sufficient; with less than this amount of zinc, or if the acid contains a little water, a longer time will be required. In general I boil the mixture until HCl ceases to be 60 evolved, and for an hour or so longer.

It will be understood that glacial acetic acid is given as an instance of the fatty acids, and that formic, propionic, stearic, etc., can be employed, but since these are 65 generally more expensive, the acetic is pre-

ferred. Benzoic or salicylic acid can also be used. Likewise in place of the pinene hydrochlorid, the compounds of other hydrohaloid acids (e. g. HBr and HF) can be used.

70 I claim:

1. A process of manufacturing an isobornyl ester and camphene mixture, which comprises heating together a mixture comprising a hydrohaloid of pinene and a carboxylic acid, in the presence of an amount of zinc corresponding to not substantially more than 5% of the amount of hydrohaloid of pinene.

75 2. A process of manufacturing an isobornyl ester and camphene mixture, which comprising maintaining at a boiling temperature a mixture comprising a hydrohaloid of pinene and a carboxylic acid, in the presence of an amount of zinc corresponding to not substantially more than 5% of the amount of hydrohaloid of pinene.

80 3. The process of transforming pinene hydrohaloid into an isobornyl ester and camphene mixture, which comprises heating to 85 the boiling point a mixture of pinene hydrohaloid and a substantially anhydrous fatty acid, in the presence of about 2 to 3% of zinc in a form substantially coarser than zinc dust.

90 4. The herein described product comprising in addition to free fatty acid and zinc salts, not substantially less than 70 parts of isobornyl ester of a fatty acid, about 10 parts of camphene and about 5 parts of camphene 100 hydrohaloid, together with not substantially more than 10 parts of unconverted pinene hydrohaloid and not substantially more than 5 parts of high boiling condensation products.

95 5. The herein described product comprising, in addition to free fatty acid and zinc salt, about 83 to 85 parts of isobornyl ester of a fatty acid, about 10 parts of camphene and 5 parts of camphene hydrohaloid, together with a small quantity of unconverted pinene hydrohaloid and not substantially more than 5 parts of high boiling condensation products.

105 6. A process of manufacturing an isobornyl ester and camphene mixture, which comprises heating together a mixture comprising a hydrochlorid of pinene and a carboxylic acid, in the presence of an amount of zinc corresponding to not substantially 110 more than 5% of the amount of hydrochlorid of pinene.

115 7. The process of transforming pinene hydrohaloid into an isobornyl ester and camphene mixture, which comprises heating to 120 the boiling point a mixture of pinene hydrohaloid and a substantially anhydrous fatty acid, in the presence of about 2 to 3% of zinc.

125 8. A process of manufacturing an iso-

bornyl ester and camphene mixture which comprises boiling together, for about 18 hours, a mixture comprising a hydrohaloid of pinene and a carboxylic acid, in the presence of an amount of zinc corresponding to about 2% of the amount of hydrohaloid of pinene.

5. 9. A process of manufacturing an iso-

bornyl ester and camphene mixture, which comprises heating together a mixture comprising a hydrohaloid of pinene and acetic acid, in the presence of an amount of zinc corresponding to not substantially more than 5% of the amount of hydrohaloid of pinene.

10. In testimony whereof I affix my signature. 15

LAURENCE G. WESSON.
